FIG. 2

UNITED STATES PATENT OFFICE.

BENJAMIN BROIDO, OF NEW YORK, N. Y., ASSIGNOR TO THE SUPERHEATER COMPANY, OF NEW YORK, N. Y., A CORPORATION OF DELAWARE.

BOILER WITH SUPERHEATER.

Application filed February 6, 1922. Serial No. 534,478.

To all whom it may concern:

Be it known that I, BENJAMIN BROIDO, a citizen of the United States, and resident of the city of New York, N. Y., have invented 5 certain new and useful Improvements in Boilers with Superheaters, of which the following is a specification.

My invention relates to the use of superheaters in connection with water tube boilers 10 of the type often referred to rather loosely as the vertical type. In this type there are two or more, usually three, upper drums, and one or more lower drums, the upper drums being connected to the lower drum or 15 drums by banks of tubes. The object of the invention is to provide an improved superheater arrangement in such boilers, whereby high degrees of superheat may be obtained; the headers and the connections of the superheater elements be protected from excessive 20 heat and at the same time remain accessible for inspection, etc.; the removal and replacement of elements of the superheater be easily effected; all of the superheater elements be self-draining; and withal the operation of the boiler be not interfered with 25 by the presence of the superheater.

The following description to be read in connection with the accompanying drawings, 30 will make clear the nature and operation of my invention. In said drawings Fig. 1 shows in longitudinal section a water tube boiler of the type spoken of with a superheater installed according to my invention. Fig. 2 illustrates on a larger scale, a 35 somewhat modified form of my invention in another well known boiler of this general type; and Fig. 3 shows still another arrangement in a third boiler of this general type, the scale of this figure being the same as that of Fig. 1.

Referring first to Fig. 1, the boiler has a front, a middle, and a rear upper drum, numbered respectively 1, 2, and 3, and connected by banks of tubes 4, 5, and 6 respectively to the lower drum 7. Drums 1 and 2 are connected to each other by a set of tubes 8, and drums 2 and 3 by a set of tubes 9. A casing 10 encloses the boiler.

11 is the combustion chamber, bounded at 50 the rear by bridge wall 12; while 13, 14, and 15 are baffles to guide the gases on their passage from the combustion chamber 11 to the stack connection 16. Steam is taken off at the nozzle 17. All of these parts are of a 55 usual construction.

Various ways have been proposed of installing superheaters in boilers of this type, the places suggested ranging from near the point where the gases finally leave the boiler 60 to a location in some part of the firebox itself. Perhaps the location best adapted from all points of view is between the first two banks of water tubes. At this point the gases have ample heat to furnish the high 65 degree of superheat which engineers everywhere are beginning to demand, and yet have in their passage over the first bank of tubes become tempered sufficiently to remove any danger of injury to the superheater 70 from excessive temperatures. This has been recognized by many, and various forms of superheaters have been devised for use in this space. None of them, however, meet all the requirements of best practice. In some 75 the headers of the superheaters are quite inaccessible so the joints between the elements and the headers cannot readily be inspected and repaired; in others the arrangement does not permit of ready drainage of moisture from the superheater; others block the passage of the heating gases so the operation of the boiler is interfered with; and others have still other faults.

In my arrangement the superheater elements 18 are placed in parallel vertical planes in the upper part of the triangular space between the first and second banks of water tubes. The ends 19 and 20 of the elements extend backward between the rows of tubes of bank 5 and are bent downward to the headers 21 and 22, to which they are secured preferably in some readily detachable manner. If desired, the headers may be additionally protected by inserting the baffle 25, which reduces the proportion of gases passing into the triangular space between baffles 14 and 15. On the other hand the

principle of my invention would be equally employed even if baffle 14 were omitted. In fact, this principle is broadly that the main portion of the superheater elements 5 lies on the side of the bank of water tubes nearest the source of hot gases and the headers to which the elements are attached lie on the farther and therefore cooler side of the bank where they are protected by the water 10 tubes, and in some cases a baffle, from the more intense heat. Obviously this principle is of use no matter whether it is the first, second or third bank of a boiler of this type which separates the two; and it is particularly pointed out that the drawings must 15 be regarded as illustrative only and not as limiting my invention in this respect.

The elements are supported by the transversely extending bar 23 and by hangers 24. 20 The operation of a boiler equipped as described will be obvious. The manner of removal of elements for repairs or replacements may however be briefly described. To effect such removal, the connection of 25 the element in question with the headers 19 and 20 is broken, and the element is withdrawn through the opposite space between tubes in bank 8, the necessary part of the roof resting on the top of this bank of tubes 30 having been removed. As an alternative which may in some cases be preferable the element after being detached from the headers may be moved through the appropriate space between rows of tubes in bank 35 4 into the combustion chamber 11 and thence out through the firing door.

It will be noted that the advantages above spoken of are obtained in any arrangement.

40 Referring next to Fig. 2, the superheater elements 18 are seen to extend not only within the space between the first two banks of tubes, but into the spaces between the tubes of the first bank 4. This will be ad- 45 visable in some cases where, as in the one shown, the space between the banks is so small that a superheater of adequate size cannot be accommodated within it. The principle above pointed out is preserved here, the headers 21, 22 lying on the side of a bank away from the source of hot 50 gases and the superheater elements on the side toward it.

In Fig. 3 a boiler is shown having three 55 upper drums, 1, 2, and 3 and three lower drums, 7^a, 7^b, and 7^c, connected respectively by the three banks of tubes 4, 5, and 6.

The superheater elements are placed in 60 the space between the banks 4 and 5, and are shown as of somewhat different form, each being made up of two branches 18^a and 18^b, connected to the two Y's 18^c and 18^d, which in turn are connected to the headers 21 and 22 by the lengths 18^e and 18^f 65 extending through bank 5.

The arrangements shown illustrate sufficiently that my invention has application to various boilers and that the details may be considerably varied without departing from its spirit. 70

What I claim is:

1. In apparatus of the class described, the combination of a boiler having a front, a middle, and a rear upper drum and a lower drum and three banks of water tubes connecting the three upper drums to the lower drum; superheater elements in the space between the front and the middle banks of tubes; and superheater headers in the space between the middle and rear banks; the elements being connected to the headers by portions extending between rows of tubes in the middle bank. 75

2. In apparatus of the class described, the combination of a boiler having a front, a middle, and a rear upper drum and a lower drum and three banks of water tubes connecting the three upper drums to the lower drum; superheater elements in the space between the front and the middle banks of tubes; and superheater headers in the space between the middle and rear banks and in a plane below the superheater elements; the elements being connected to the headers by portions extending between rows of tubes 90 in the middle bank.

3. In apparatus of the class described, the combination of a boiler having a front, a middle, and a rear upper drum, a lower drum, three banks of tubes connecting the three upper drums to the lower drum, and a bank of tubes connecting the front and middle upper drums; superheater elements in the space between the front and the middle banks of tubes; superheater headers in the space between the middle and rear banks; the elements being connected to the headers by portions extending between rows of tubes in the middle bank; and means extending between rows of tubes connecting 100 the front and middle upper drums supporting the superheater elements. 105

4. In apparatus of the class described, the combination of a front, a middle, and a rear upper drum, a lower drum, three 110 banks of tubes respectively connecting the three upper drums to the lower drum; a baffle extending behind the first bank of tubes from the lower drum and terminating short of the upper front drum; a baffle behind the second bank of tubes; superheater elements in the space between the front and the middle banks of tubes; and superheater headers in the space between the middle and rear banks; the elements being connected 115 to the headers by portions extending between rows of tubes in the middle bank and through the second named baffle.

5. In apparatus of the class described, the combination of a front upper drum, a 120

second upper drum, and a lower drum, a front and a second bank of tubes connecting the upper drums respectively to the lower drum, means to cause hot gases to pass first over the front and then over the second bank, a pair of superheater headers adjacent to the second bank of tubes, and a plurality of tubular superheater elements between the two banks of tubes, said elements having portions extending between 10 rows of tubes of the second bank connecting the elements to the headers.

BENJAMIN BROIDO.
